UNITED STATES PATENT OFFICE.

JOSEPH T. CRAW, OF JERSEY CITY, NEW JERSEY, ASSIGNOR OF ONE-HALF
TO ROBERT P. BROWN AND EDWARD L. BAILEY, OF PHILADELPHIA,
PENNSYLVANIA.

PAPER BOX.

SPECIFICATION forming part of Letters Patent No. 656,948, dated August 28, 1900.

Application filed May 23, 1900. Serial No. 17,660. (No model.)

To all whom it may concern:

Be it known that I, JOSEPH T. CRAW, a citizen of the United States, and a resident of Jersey City, in the county of Hudson and State of New Jersey, have invented a new and useful Improvement in Paper Boxes, of which the following is a full, clear, and exact description.

One purpose of the invention is to provide 10 a slide-box adapted as a package for tacks or other small articles, and to so construct the box that it will be made from a single blank, and to so fold the members of the blank and connect certain of said members that a tube 15 or body and a sliding tray are obtained, the tray being capable of complete withdrawal from the tube or body and spreading apart at such time, so that all the contents of said tray will be rendered accessible.

Another purpose of the invention is to so 20 construct the box that the tray may freely slide in the tube or body while constituting a portion of the latter and so that when the tray is withdrawn from the body and spread 25 the tray may be quickly restored to its position within the tube or body.

The invention consists in the novel construction and combination of the several parts, as will be hereinafter fully set forth, 30 and pointed out in the claims.

Reference is to be had to the accompanying drawings, forming a part of this specification, in which similar characters of reference indicate corresponding parts in all the figures.

Figure 1 is a plan view of the blank from 35 which the box is made. Fig. 2 is a bottom plan view of the said blank folded flat or in shape for transportation. Fig. 3 is an edge view of the blank when in the position shown 40 in Fig. 2. Fig. 4 is a perspective view of the improved box complete, the tray being within the tube or body. Fig. 5 is a perspective view of the complete box, showing the tray withdrawn from the body or tube and spread 45 so that any of its contents may be reached. Fig. 6 is a longitudinal vertical section through the box when the parts are in the position shown in Fig. 4. Fig. 7 is a longitudinal vertical section through the box when the parts 50 are in the position shown in Fig. 5, and Fig.

8 is a transverse section through the box when the tray is within the tube or body.

The parts or sections of the box comprise a tube or body A and a tray B. These two parts or sections are made from a blank constructed from a single piece of material, stiff paper being preferred. That section of the blank which is to form the tube or body A consists of a central end panel 10 and adjacent parallel panels 11 and 12, these panels being separated from each other by score-lines *a* and *a'*. At the ends of the central panels 10, 11, and 12 panels 13 and 14 are located, which extend transversely to the length of the central panels, and these panels 14 and 13 are adapted to form the sides of the tube or body of the box, while the central panels 10, 11, and 12 form the upper portion of the said tube or body. The side panels 13 and 14 are divided from the central panels of the blank 70 or those panels which constitute the top of the tube or body by score-lines *a*² and cuts *a*³, the score-lines extending at the ends of the panel 10, while the cuts *a*³ are located at the ends of the panels 11 and 12, thus 75 separating these panels from the side panels 13 and 14. The side panel 13 is provided with an additional panel 15, separated therefrom by a score-line *b*, and this panel 15 is adapted to constitute a portion of the bottom of the tube or box, the remainder of the bottom being formed by a larger panel 16, separated from the side panel 14 by a score-line *b'*. That section of the blank which is adapted to form the sliding tray B consists 80 of a central panel 17, having panels 18 and 19 adjacent to opposite ends and separated from the central panel 17 by score-lines *c*' and *c*². The panel 18 is adjacent to the panel 12 of the body or tube of the box and is separated 85 therefrom by a score-line *c*. An outer panel 20 forms an extension from the panel 19, being separated therefrom by a score-line *c*³, and this panel 20 acts in the nature of a closing-flap. When the completed box is 90 formed and the sliding tray is within the tube or body A, the panels 18 and 19 constitute the closing ends of the box.

Side panels 21 and 22 are located at opposite sides of the central panel 17, separated 100

therefrom by score-lines c^4 and c^5 , and these panels 21 and 22 constitute the sides of the sliding tray. The side panels 21 and 22 of this sliding tray are provided with extension-
 5 panels 23 and 24, respectively, which panels 23 and 24 are likewise adapted to act in the capacity of flaps. The panels 23 and 24 are separated from the side panels 21 and 22 by score-lines c^6 and c^7 . End flaps 25 and 26 are located at the end portions of the side panels 21 and 22 of the sliding tray adjacent to the portion of the blank from which the tube or body is formed. These end flaps 25 and 26 are separated from the panel 18 by cuts d'
 10 and from the side panels 21 and 22 by score-lines e . At the outer edges of the end flaps 25 and 26 auxiliary flaps 27 are located, divided from the main flaps 25 and 26 by score-lines d . Cuts d^2 separate the main end flaps
 15 25 and 26 and their auxiliary flaps 27, respectively, from the side panels 13 and 14 of the body portion of the blank and the connected panel 15 and the opposing side panel and connecting panel 16, which constitute a portion of the bottom of the body or tube of the box. Cuts d^3 likewise separate the auxiliary flaps 27 from the panels 23 and 24, connected with the side panels 21 and 22 of the sliding-tray section.
 20 At the opposite or outer ends of the side panels 21 and 22 of the sliding-tray section of the blank end flaps 28 and 29 are located, and auxiliary flaps 30 are connected with the outer side portions of the said end flaps 28 and 29. The end flaps 28 and 29 are separated from the side panels 21 and 22 by score-lines d^4 , and cuts d^5 separate these end flaps 28 and 29 from the central outer panel 19, which is adapted to constitute an end portion
 25 of the sliding tray, the panel 20 extending beyond the flaps 28 and 29. Score-lines d^7 separate the flaps 28 and 29 from the auxiliary flaps 30, and the auxiliary flaps 30 are separated from the outer side panels 23 and 24 by cuts d^4 . It will be observed that the score-lines d , c^6 , and d^7 are nearer the center of the tube or body section of the blank than the score-lines b , produced upon said tube or body section, and the same arrangement of
 30 score-lines is preserved between the line b' on the tube or body portion of the blank and the lines d , c^7 , and d^7 on the sliding-tray section, so that when the tray is formed it will readily enter and slide in the tube or body, as the tube or body will be of greater trans-
 35 verse dimensions than the corresponding dimensions of the sliding tray.

In forming the box the side panels 21 and 22, with their outer connected panels 23 and 24, together with the end flaps 25 and 26, 27, 28, 29, and 30, are folded down flat upon the central panels of the sliding-tray section of the blank, which central panels include the panels 17, 18, 19, and 20. The side panels 13
 40 and 14 of the body portion of the blank are then carried up at right angles to the top por-

tion of this section of the blank, including the panels 10, 11, and 12, and the panels 15 and 16 are then carried in direction of each other at right angles to the side panels 13 and 14, 70 and the panels 15 and 16 are thereupon glued together or otherwise secured. The body or tube portion A of the box is thus formed; but prior to gluing or connecting the panels 15 and 16 the sliding-tray portion of the blank 75 in its folded condition is carried over upon the panels 10, 11, and 12 of the body or tube portion of the blank, as shown in Fig. 2, and the body portion of the blank in its folded state is then pressed flat to facilitate connecting the two panels 15 and 16 of the body. The bottom of the box will now be uppermost, and in order that a person may understand that the folded blank must be reversed when the box is to be filled the words "Turn over" 80 are preferably printed upon an exposed portion of the sliding-tray section B, as is also shown in Fig. 2. The blanks when flattened, as shown in Fig. 2, are readily transported and a number of them can be packed in a 90 small compass.

When it is desired to fill the tray with tacks, for example, a blank occupying the position shown in Fig. 2 is turned over or reversed and the body portion of the blank is straightened out to a rectangular shape. The sliding-tray section B is now drawn out from the body, whereupon the panels 11, 12, and 18 will fold downward in the body or tube, and when the panel 11 is at right angles to the bottom of 100 the tube or body, as shown in Figs. 5 and 7, the panel 18 will extend beyond an end of the tube or body and the sliding tray will have been entirely withdrawn from the body of the box. The side flaps 21 and 22 of the 105 tray are now bent upward and the end flaps 25, 26, 28, and 29 are bent inward, as shown in Fig. 5, so that corresponding flaps at the ends will practically overlap or engage. A tray is thus formed for the reception of material, and after a suitable amount of material has been placed in the tray the auxiliary flaps 27 and 30, connected with the end flaps 25, 26, and 28, 29, are bent inward over the material, and the panels 23 and 24, connected 110 with the side panels 21 and 22, are likewise bent inward over the material and over the auxiliary end flaps. Thus it will be observed that the panels 23 and 24 constitute flaps and serve to hold the end flaps in position. The end panel 19 of the sliding tray is now carried upward and the extension or auxiliary panel 20 is bent over upon the folded flaps at that end of the sliding tray, so that the panel 20 virtually constitutes a locking-flap. The inner end of the tray thus folded is made to enter the tube or body and is pressed inward until the closing or sealing flap 20 has passed beneath the panel 10, forming a portion of the top of the box and a square 120 package is obtained. By folding the flaps at the outer edges of the tray, as stated, the tray 125

is capable of sliding with perfect freedom in the tube or body.

It will be observed that the box can be opened from one end only—namely, that end at which the sliding tray connects with the body—and instructions to this effect are generally printed at this end of the box.

Under the construction of box above set forth a package is obtained, including a body 10 and a tray sliding therein, all made from one piece of material, and the tray may be entirely withdrawn from the body, as shown in Fig. 5, and its members spread apart, enabling any particular article in the tray to be readily selected, inspected, or taken up. The members of the tray may be quickly assembled and the tray in its closed position quickly and conveniently introduced into the body or tube and completely concealed thereby.

Having thus described my invention, I claim as new and desire to secure by Letters Patent—

1. In folding boxes, a body, and a tray having side and end members and held to slide 25 in the body, the tray being continuous with a member of the body and the connection between the tray and the body being such that the tray may be withdrawn its full length from the body and its contents be fully exposed.

2. In a paper box, a body and a tray mounted to slide in the body, the tray and body being constructed of one piece of material, the said tray having side and end members and 35 having a folding connection with a member of the body, the side and end members of the tray being arranged to spread apart when the tray is withdrawn from the body, as set forth.

3. In a paper box, a body and a tray adapted to slide in the body, which tray and body are constructed from one continuous piece of material, the direct connection between the tray and body being at one surface and free of opposing side surfaces of the body, the said 45 tray being capable of extending its full length beyond the body, and the connection between the tray and body being such that a portion

of the body folds within the same, when the tray is withdrawn, as set forth.

4. In a paper box, a body, and a tray held 50 to slide in the body, both the body and the tray being made from a single piece of material, the connection between the tray and the body being at the top of the latter between its ends and said connecting medium being 55 free from attachment to the side portions of the body, the said tray having a bottom, side sections free to fold outward and provided with inwardly-extending flaps, end flaps likewise free to fold outward carried by said sections and having auxiliary flaps adapted to extend over the material within the tray, and an end panel forming a continuation of the bottom and provided with a locking-flap 60 adapted to enter the body when the tray is 65 in position therein, for the purpose described.

5. A paper box comprising a body, a tray adapted to slide in the said body, which tray and body are constructed from a single piece of material, the tray having a folding connection with the body at a point between its ends, the said tray being likewise adapted to be drawn its full length from the body, and side and end sections of the tray having movement in an outward or inward direction, as 75 set forth.

6. In a paper box comprising a tube or body and a sliding tray, a blank comprising end panels and flaps 10, 11, 12, 13, 14, 15 and 16, tray panels and flaps 17, 18, 19, and 20, 21, 22, 80 23, 24, 25, 26, 29 and 30, the flaps 25 and 26 being separated from the panels 13 and 14 and likewise the flaps 27, the flaps 27 and 30 being separated from the flaps 23 and 24, and the flaps 28 being separated from the panel 85 19, as described.

In testimony whereof I have signed my name to this specification in the presence of two subscribing witnesses.

JOSEPH T. CRAW.
